Inventor:

Jacob Jacoby
Philadelphia, Pa.

United States Patent Office.

JACOB JACOBY, OF JOHNSTOWN, PENNSYLVANIA.

Design No. 4,984, dated May 30, 1871.

DESIGN FOR WEATHERBOARDING.

The Schedule referred to in these Letters Patent and making part of the same.

To all whom it may concern:

Be it known that I, JACOB JACOBY, of Johnstown, in the county of Cambria and State of Pennsylvania, have invented a new and original Design for Weatherboarding; and I do hereby declare that the following is a full, clear, and exact description of the same, reference being had to the annexed drawing making a part of this specification, and to the letters and figures of reference marked thereon.

The nature of my design is fully represented in the accompanying photographic illustration.

The profile of this weatherboarding is designed to allow a free movement of water downward on its face, and at the same time the curves and angles are so shaped that the water will not drop from one portion

to another, but will be guided in and out over every part of the weatherboard face.

Therefore, while a weatherboard of this profile will not provide any hollows or ledges which will retain moisture to rot it, the water which falls on it will have free access to all parts of the face, keeping them equally clean.

I claim as my invention—

The design for a weatherboarding, as shown.

In testimony that I claim the above I have hereunto subscribed my name in the presence of two witnesses.

Witnesses:

JOSEPH KUNTZ,
D. C. MORRIS.

JACOB JACOBY.
